SKIN, HIDE, AND LEATHER WORKING
MACHINE

Frank Wayland, Camden, N. J.

Application March 23, 1938, Serial No. 197,604

1 Claim. (Cl. 149—16)

This invention relates to machines for staking, putting-out, fleshing and otherwise working skins, hides and leather and has particular reference to leather working machines of the class shown and described in my United States Patents Nos. 1,077,207; 1,131,756; 1,204,914 and 2,109,739.

The object of my present invention is to improve the construction and mode of operation of machines of the class referred to and to this end I have provided certain improvements as set forth in the following description, the several novel features of the invention being separately pointed out and defined in the claim at the close thereof.

15 In the accompanying drawings:

Figure 1 is a front elevation of my improved leather working machine.

Figure 2 is an end elevation of the machine shown in Fig. 1.

20 Figure 3 is a section on line 3—3 of Fig. 1.

The illustrated embodiment of my invention comprises a frame including a base 10 and two spaced apart upright sections 11, 11 fixed in position upon said base.

25 The upright frame sections 11 have bracket extensions 12 fixed rigidly in position on their tops adjacent to the rear of the machine and these extensions constitute rigid parts of the frame of the machine which are constructed with 30 alined bearings in which a transverse shaft 13 is journaled.

35 Between the extensions 12 the shaft 13 carries a feed roll 14 and at one side of the machine it has fixed thereon a pulley 15, Fig. 1, that is driven by a belt indicated by dotted lines at 16.

The feed roll 14 is co-operatively associated with another feed roll 17 carried by a shaft 18 journaled at its opposite ends in two supplemental boxes 19, one of which is provided above each 40 upright frame section 11.

Below the feed rolls 14 and 17 is provided a pair of bladed work rolls 20 and 21, the former being fast on a shaft 22 journaled in bearings provided in the extensions 12 of the frame and the latter 45 being fast on a shaft 23 journaled in main boxes 24 slidably mounted upon the tops of the upright frame sections 11. The boxes 24 are held in position on the frame sections 11 by guide rods 25, each of which is fastened at its one end to its 50 frame section 11 as at 26, Fig. 2, and extends therefrom loosely through a hole formed through its box 24 and into a socket 27 formed in the extension 12 of said section.

55 Thus the frame of the machine is constructed with parallel ways on which the boxes 24 are slid-

able back and forth to shift the front work roll 21 bodily toward and from the rear work roll 23, the latter being driven always in the direction of the arrow a, Fig. 3, by means of a belt 28 applied to a pulley 29 fast on the shaft 22 of said rear work roll 23.

The shaft 22 of the rear work roll 23 has fixed on it a gear 30, Fig. 2, meshing with a gear 31 that is loosely mounted upon a stud shaft 32 projecting from the frame of the machine. Gear 31 10 drives a "floating" gear 33 which, in turn continuously drives a gear 34 fast on the shaft 23 of the front work roll 21 so as to rotate said front roll continuously in the direction of the arrow b, Fig. 3, at the same peripheral speed as that of 15 the rear work roll 23.

The gear 33 is loosely mounted upon a stud shaft 35 projecting from the lower end of a link 36 whose upper end is pivotally mounted upon the shaft 23 of the front work roll. This link 20 36 holds the gear 33 in mesh with gear 34 while a second link 37 pivotally mounted at its opposite ends upon the stud shafts 32 and 35, respectively, holds the gear 33 in mesh with the gear 31. It will thus be clear that the above described 25 gearing including the two links and the floating gear 33 provide a flexible power transmitting mechanism through which the rear work roll shaft continuously drives the front work roll shaft so as to provide for movement of the latter 30 toward and from shaft 22.

Mechanism is herein provided that is manually operable to shift the slides or boxes 24 and parts carried thereby on the frame of the machine to simultaneously open or close the feed rolls and 35 the work rolls thereby to permit the work W, Fig. 3, to be inserted and operated upon by the machine or to be removed from the latter. This mechanism may comprise two toggles 38, one for each slide or box 24, a foot lever 39 and two links 40 connecting the knees or middle joints of the toggles with the foot lever 39.

One end of each toggle 38 is pivotally connected as at 41 with one of the slides or boxes 24 while its opposite end is pivotally connected 45 as at 42 to a bracket 43 fastened by a screw 44 to the proximate upright frame section 11 so that it can be adjusted toward and from the box or slide 24 and fixed in its adjusted position. An abutment screw 45 adjustably mounted on the 50 frame of the machine bears against the front side of bracket 43 to prevent accidental displacement of the latter.

The foot lever 39 comprises a pair of arms fulcrumed on a shaft 46 mounted in brackets 47 fast 55

on the top side of base 10 and the free ends of the arms of the foot lever are connected by a foot board or bar 48 fastened at its opposite ends to said arms. Thus, by foot pressure on the cross-bar 48 the lever 39 acts through the links 40 to force the knees or middle joints of the toggles downwardly thereby forcibly shifting the boxes or slides 24 toward the rear of the machine so as to cause the feed roll 17 to force the sheet material W against the continuously rotating feed roll 14 and so as to cause the blades of the work roll 21 to intermesh with the blades of the rear work roll 20.

The work rolls 20 and 21 are constructed with spiral blades after the manner of the work rolls 14 and 15 of my Patent No. 2,109,739 referred to above and they operate in the usual fashion to stretch the material W longitudinally and laterally in opposite directions from its middle and 20 to also flex and scrape the material W as heretofore.

Each supplemental box 19 is mounted upon one of the lower main boxes or slides 24 and connected therewith by means of a rod 49, Figs. 2 25 and 3, which extends loosely through holes formed in the boxes 19 at right angles to the shaft 18. Each rod 49 is fixed at one end to its lower box or slide 24 while its opposite end is slidably mounted within a socket 50 formed through the 30 frame extension 12.

The lower box or slide 24 is made with an up-standing lug 51 formed with a threaded hole through which extends a screw 52 whose outer or forward end is made with a handle 53 and 35 whose inner end is swivelly connected with the upper box or slide section 19 as at 54. As will be clear, the screw 52 not only holds the upper box 19 rigidly in adjusted position on the lower box or slide 24 but by rotating said screw said upper 40 box may be adjusted toward and from the driven feed roll 14 as may be required to secure the proper intermeshing of the work rolls 20 and 21.

Between and secured at its opposite ends to the upper boxes 19 is a flat table 55 on to which 45 the skin, hide or leather W is placed and held by the operator while the machine operates upon said material W. The operator stands upon the base 10 with one foot upon the crossbar 48 of the treadle and by operating the latter with his 50 foot can open and close the feed rolls and work rolls as required in inserting, operating upon and removing the sheet material W.

In staking leather the latter is laid upon the table 55 and slid forward thereon so as to place 55 its forward end between the feed rolls while the latter are open, then the operator presses downwardly upon the treadle 39 and closes the rolls so that the latter engage the material while the feed roll 14 is driven in the direction of the arrow 60 c in Fig. 2 at a peripheral speed that is less than the peripheral speeds of the work rolls 20 and 21. When the leather has been fed into the machine a predetermined distance the operator relieves the treadle 39 of foot pressure whereupon a weight 56 65 acts through said treadle and the mechanism connecting the same with the boxes or slides 24 to

shift the latter away from the rear work roll 20 and the rear feed roll 14. The leather is then reversed end for end on the table 55 and again fed into the machine a pre-determined distance whereupon it is again released and removed, 5 which completes the operation of staking.

In putting-out and other operations the feed roll 14 may be driven in the direction indicated by the arrow d after inserting the work W into the machine between the work rolls and the feed rolls 10 and then when the rolls are closed the feed rolls will forcibly draw the skin upwardly between the work rolls and discharge it from the machine. Thus a reversible drive for the feed roll 14 may be provided as set forth in my Patent #2,109,739, al- 15 though said reversible drive is not herein illustrated.

Because of the simplicity of its construction the above described machine is very much less expensive to construct than my prior machines of 20 this class and is of greater efficiency than the latter for the reason that the feed rolls and work rolls can be opened and closed by the operator instantly by means of the foot treadle, whereas in the machines of this class heretofore provided 25 the two front rolls were carried by a swinging frame operated by an eccentric on a countershaft at the rear and it was necessary for this eccentric to make one-half of a revolution to open the rolls and one-half of a revolution to close the rolls 30 and these operations were much slower than in the present machine.

What I claim is:

In a machine of the character described, the combination of a pair of opposed spirally bladed 35 intermeshing work rolls for simultaneously engaging the opposite sides of the sheet material that is operated upon; means for continuously rotating said rolls to cause the same to flex and scrape said material and also to stretch the same 40 longitudinally and transversely; a pair of opposed feed rolls disposed above and adjacent to said work rolls so as to coat with the latter in stretching the material longitudinally; a main 45 frame on which one roll of each of said two pairs is journaled; two main journal boxes slidably mounted on said main frame so that they are movable toward and from the two rolls which are mounted on the latter, said main journal boxes rotatably supporting the other work roll; 50 two supplemental journal boxes each of which is mounted on one of said main journal boxes so that it is slidably adjustable thereon toward and from the two rolls which are mounted on said main frame, said supplemental journal boxes rotatably supporting the other feed roll; means for 55 fixing each supplemental journal box in its adjusted position on its main journal box, and foot-operated toggle mechanism operable to slide said main journal boxes on said main frame toward and from the two rolls which are mounted upon the latter, movement of said journal boxes toward said last-mentioned rolls being limited by the engagement of said two feed rolls with the work. 60
